DESIGN FOR A CHAIR OR SIMILAR ARTICLE

Jackson D. Rogers, Bay Village, Ohio

Application March 17, 1937, Serial No. 68,205

Term of patent 7 years

To all whom it may concern:

Be it known that I, Jackson D. Rogers, a citizen of the United States and resident of Bay Village, in the county of Cuyahoga and State of Ohio, have invented a new, original, and ornamental Design for a Chair or Similar Article, of which the following is a specification, reference being had to the accompanying drawing, forming a part thereof.

In the drawing, the figure is a perspective view of a chair, showing my new design, the characteristic feature of which resides in the contour of the seat and back members shown in full lines.

I claim:

The ornamental design for a chair or similar article, as shown and described.

JACKSON D. ROGERS.
